UNITED STATES PATENT OFFICE.

WILLIBALD GRUN, OF FRANKFORT-ON-THE-MAIN, GERMANY.

REGULATION OF ROTARY COMPRESSORS.

1,372,502.

Specification of Letters Patent.

Patented Mar. 22, 1921.

Application filed March 14, 1912, Serial No. 683,750. Renewed November 12, 1919. Serial No. 337,622.

To all whom it may concern:

Be it known that I, WILLIBALD GRUN, a citizen of the German Empire, and a resident of Frankfort-on-the-Main, Germany, have invented certain new and useful Improvements in the Regulation of Rotary Compressors, of which the following is a specification.

It has been impossible hitherto to devise a satisfactory economical regulation of rotary compressors, without losses occurring through throttling in the suction conduit or the delivery conduit. Various methods have been proposed, but they have proved defective for reasons more fully set forth herein-after. The object of my present invention is to provide a regulator combining the advantages of devices previously employed, yet avoiding or neutralizing their defects. With my improved regulator, the number of revolutions of the compressor is adjusted, within wide limits, automatically by the pressure or the amount of the air delivered by the compressor, yet at the same time, a speed regulator keeps the number of revolutions as nearly constant as possible. Seemingly, these two results are incompatible with each other, but I secure them jointly by providing a speed regulator adjustable to different normal or regular speeds, but operating to keep the number of revolutions constant as long as the adjustment is not changed, a different normal number of revolutions corresponding to each particular adjustment; the adjustment of this speed regulator or governor is effected by the device which regulates the pressure or output of air, an increase in the number of revolutions of the compressor being accompanied by the setting of the speed governor for a higher number of revolutions.

Various forms of my invention are illustrated by the accompanying drawings, in which—

Figures 1, 1^a, 2, 4, 7 and 8 are diagrammatic views of six different embodiments of my invention; Fig. 9 is a detail showing another form of regulator to be used in connection with my invention; and Figs. 3, 5 and 6 are pressure and output diagrams serving to explain the nature and advantages of my invention.

In most cases, as practised hitherto, the regulation of rotary compressors has been effected by means of a speed regulator (governor) tending to keep the number of

revolutions of the compressor approximately constant. The operation of this old governor is represented by the curve A—B of Fig. 3, in which the ordinates represent the air pressure P and the abscissæ the output or quantity of air Q, for the constant numbers of revolutions n' , n^2 , n^3 , n^4 , n^5 , n^6 . The curve A—B shows that any variation in the output or delivery of air is accompanied by a material change in air pressure. Another drawback of this method is that it allows the capacity of the compressor to be varied only within restricted limits, and the output of air may therefore be reduced but slightly below the normal output, since otherwise the operation will become unsteady or jerky.

Another method of regulation which has been proposed consists in utilizing the static or dynamic effects of the air, that is to say, in making the regulation dependent upon the pressure or the flow of air; so that this mode of regulation will keep the air pressure or the flow of air respectively approximately constant. Devices working on this principle are combined with a governor (ball governor) of the well-known character, to prevent any excessive rotary speed. The operation of a pressure regulating device of this type is represented by the line A—C of Fig. 3. This method, by varying the number of revolutions, keeps the air pressure almost constant, and allows the capacity of the compressor to be varied within considerably wider limits than according to the old method first referred to above, yet it is open to the serious objection that not only air pressure, but other factors as well will affect the number of revolutions, and this is particularly detrimental in the case of rotary compressors. Assuming, for instance, that the capacity of the compressor is adjusted by an air pressure governor, to the value corresponding to the point D on the curve 3 of Fig. 3, and that then the driving mechanism of the compressor fails suddenly, the regulation will not be affected, since at first the pressure in the compressed air piping (delivery pressure) will remain unchanged. In the event of a failure of the driving mechanism, the number of revolutions of the compressor will however fall at once say to n^6 (curve 6) and of course with this reduced number of revolutions the compressor will not be able to produce the required delivery.

pressure in the distributing pipes, but will work in a jerky fashion, so that a regular operation will become impossible. This behavior is of particular importance when the 5 compressor is driven by means of turbines adapted to be operated at one or the other of two pressures, say using live steam in one case and exhaust steam in the other; the change from one mode of operation to 10 the other tends to disturb the even running of the machine.

If on the other hand regulation is accomplished by means of a device governing the flow of air, which device is actuated by 15 the flow of the air either directly or indirectly, as by the differential pressure effect at two points of the stream of air, said device being connected either with the suction conduit or with the delivery conduit 20 of the compressor, the regulating device will be adjusted according to variations in the amount of air passing through the suction conduit or the delivery conduit respectively. This adjusting operation 25 responds either to the vertical line $f-g$ of Fig. 6, or (and this is generally the case) to a line inclined slightly in the direction of the line $h-i$. That is to say, if the air pressure increases, the number of revolutions 30 of the compressor is increased to such an extent as to keep the output constant or at least to allow but a slight diminution.

As stated above, it is the object of my invention to combine the advantages of the 35 former methods of regulation while avoiding their defects.

The two embodiments of my invention illustrated by Figs. 1 and 2 are adapted particularly for use in connection with compressors operated by an engine actuated by 40 a single medium (say, live steam). A ball governor 1 of the type customary in connection with steam engines has its sleeve 2 connected pivotally with a rod 2'. At 3 this 45 rod is connected pivotally with a link 29, pivoted at 27 to the end of a lever 9. At 28 the lever is connected pivotally with the rod 17' of the piston valves 17 and 18 which are connected rigidly and move in the 50 distributing cylinder 8. The other end of the lever 9 is pivoted at 15 to the rod 14 of the piston 13 contained in the air pressure regulating cylinder 7. One face of the piston 13 is under the influence of the air pressure 55 prevailing in the pressure piping or delivery conduit, the pipe 33 being in permanent communication with said conduit; the other face of the piston 13 is engaged by a spring 16 opposing the action of said air pressure. The strength of the spring 16 determines the extent or range of variation 60 in the air pressure which is allowed for regulation purposes. At the right-hand end 4 the lever 2' in the mechanism shown in 65 Fig. 1 is pivotally connected with the rod 23

to which is secured the piston 5 working in the cylinder 22 and also the regulating element or regulating valve 6 arranged in the casing 24. This valve controls the passage of live steam or other driving agent from 70 the inlet 24' to the outlet 24'', and the steam thus passing through the valve casing 24 then travels to the turbine or other engine which drives the compressor, that is to say, the valve 6 is interposed in the pipe supplying steam to the engine which operates 75 the compressor.

A pipe 19 supplies a fluid under pressure (say, air or water) to the cylinder 8, between the two pistons 17, 18. From the 80 ends of the cylinder 8 pipes 20 and 21 lead to the corresponding ends of the cylinder 22. The ends or heads of the cylinder 8 may be perforated to allow the air or other fluid to escape from one or the other chamber of cylinder 22 through pipe 20 or 21, as the case may be, and the end chamber of cylinder 8 which at that time communicates with such pipe. The spindle 1' of the governor 1 is operatively connected with the 85 compressor or with the engine driving the compressor. The sensitiveness of the governor 1 should be but slight (say from 10 to 20%), that is to say, it should respond only to variations exceeding a certain 90 amount. In the construction illustrated by Fig. 1, the point 3 at which the lever 2' is connected with the link 29 and through it with the lever 9, is relatively close to the governor spindle 1' and thus only a small 95 portion, 10-11, of the regulating throw 10-12 will be required to bring the regulating element (valve 6) from one extreme position to the other.

The device shown in Fig. 1 operates as 105 follows:

If pressure rises in the pipe 33 connected with the delivery conduit of the compressor, the piston 13 will move upward, compressing the spring 16 and swinging the lever 9 and link 29 about the point 3 as a temporary fulcrum. The upward movement of the lever 9 lifts piston valves 17, 18 from the closing 110 position shown in Fig. 1, and thus allows fluid under pressure to pass from the pipe 115 19 to the pipe 20 and the upper end of the cylinder 22. The piston 5 is thereby caused to move downward and the valve 6 is brought toward its closed position, thus reducing the supply of steam to the engine, 120 and consequently the output of the compressor with the number of its revolutions. In consequence thereof, the governor sleeve 2 will fall and bring the piston valves 17, 18 back to the central position shown in Fig. 125 1. As long as the air pressure remains constant, the speed governor 1 will keep the number of revolutions approximately constant, say within limits of 1 or 2%. The air pressure governor or static pressure gov- 130

error or regulator constituted by the piston 13 and the parts connected therewith will cause the governor sleeve 2 to shift between the points 10 and 12 and will thus adjust 5 the number of revolutions within wide limits.

While the regulating device shown in Fig. 1 will work satisfactorily in many cases, it has the drawback that every variation in 10 the driving medium (say steam) or in the operation of the engine actuating the compressor will cause a considerable shifting of the regulating device and consequently variations in the output of the compressor. 15 Under unfavorable conditions, these variations may even defeat entirely the intended effect, since the considerable shifting movement may cause greater variations in the 20 number of revolutions of the compressor than the speed governor has been calculated for.

In order to overcome this drawback, I have devised the arrangement shown in Fig. 2. The speed governor 1, lever 2' and link 25 29 are substantially the same as in Fig. 1, except that the lever 2' has a stationary fulcrum at 4 and that the connecting point 3 is approximately midway between the ends 30 of the lever 2'. The lower end of the link 29 is connected at 27 not only with the lever 9, but with a spring 26, secured at the other 35 end to the rod 31 of a piston 30 movable in a cylinder 25 filled with oil or the like. This cylinder and piston form a dashpot, 40 the two ends of the cylinder being connected by a pipe 32 in which an adjustable valve 32' is provided to vary the effective cross section of the passage connecting the two cylinder ends. The cylinder 25 is secured to the piston rod 23. The parts 5, 6, 22, 24, 24', 24'', 20, 21, 8, 17, 18, 19, 17', 9, 27, 28, 15, 14, 16, 7, 13 and 33 are practically 45 the same as in Fig. 1, but I have added a vertically adjustable ring 16' to vary the tension of the spring 16. It will be understood that the dash-pot and the spring 26 constitute a yielding or variable length connection between the link 29 and the piston rod 23, that is to say, the connection may 50 become lengthened or shortened temporarily, but will resume its normal length when the disturbing influence ceases.

The device shown in Fig. 2 will operate as follows: An increase of pressure in the 55 delivery conduit of the compressor will, through the pipe 33, act to raise the piston 13 against the tension of the spring 16. The lever 9 is swung upward as in Fig. 1, raising the piston valves 17, 18, and allowing 60 fluid under pressure to pass from the pipe 19 to the pipe 20 and to the upper end of cylinder 22. This causes the piston 5 and valve 6 to be lowered, throttling the connection between 24' and 24''. As described above, 65 this reduces the rotary speed, causing the

governor sleeve 2 to move downward, and restoring the piston valve 17, 18 to the closing or central position shown in the drawing. This movement of the piston 5 takes place very quickly, so that the oil cylinder 70 25 (rigidly connected with the piston 5) and its piston 30 will at such time move as if they were rigidly connected with each other, and will thus put the spring 26 under tension. Thereupon the spring 26 will gradually move the piston 30 upward in the cylinder 25, causing the oil to pass from the upper compartment of the cylinder through the pipe 32 to the lower compartment. The time required for this movement may be 75 varied by adjusting the valve 32'. The effect of throttling the passage of the valve casing 24 by the valve 6 will be to slow down the speed of the engine, which will in a comparatively short interval of time affect 80 the fly-ball governor 1; at the same time, the spring 26, being under tension, will exert a force upon the pivot 3 which will tend to move the governor to the position which it will assume ultimately, viz: that corresponding to the reduced speed of the engine. Thus the spring 26 counteracts, at least in part, the sluggishness of the governor and causes it to respond more quickly to speed 85 changes than it would otherwise. The dashpot arrangement 25, 30 enables the spring 26 to return to a neutral condition, that is, a condition in which it is neither under tension nor under compression, after it has performed the function described above. When 90 100 the actuating fluid is admitted through pipes 19, 21 to the lower side of the piston 5, the operation of the spring and dash-pot will be the same as described above, except that the spring 26 would be placed under compression and not under tension. 105

The spring 26 with the cylinder 25 and piston 30 also act as an isodromic connection or device, that is, as a device for bringing the governor 1 and the engine (after 110 each regulating operation not produced by change of delivery pressure or flow) back to the original angular speed or number of revolutions as it existed before the regulating adjustment. This "isodromic" regulating action, however, occurs only as long as the piston 13 (operated by air-pressure) is stationary, so that the pivot 15 as well as the point 4 will constitute (at least for the time being) stationary fulcrums. In this 115 case the movement of the governor sleeve 2 lengthwise of the spindle 1' will at first operate the parts positively, at the same time placing the spring 26 under strain (compression or tension), but the movement of 120 valve 6 will be somewhat retarded because the movement of link 29 is partly expended in producing compression or expansion of the spring; this retarding is however compensated for as the spring gradually re- 125 130

sumes its neutral condition. If for instance, with the piston 13 at rest, the sleeve 2 of the governor 1 moves upward, the lever 9, swinging on the point 15 as its temporary fulcrum, will place the spring 26 under tension and at the same time lift the piston valves 17, 18 so as to admit the medium under pressure from the pipe 19 to the space of the cylinder 22 above the piston 5. This piston with the valve 6 will then move downward, placing the spring 26 under further tension, and the lever 9 will be pulled down, thereby bringing the piston valves 17, 18 back to their original position; this action is however retarded somewhat on account of the fact that the piston 30 does not move entirely in unison with the cylinder 25, but lags behind. At the same time, on account of the reduction in the speed of the engine due to the throttling of the steam supply, the governor sleeve 2 will tend to slide downward on the spindle 1', the tension of the spring 26 assisting in thus returning the governor sleeve and also in bringing the lever 9 and piston valve 17, 18 to the former position, in which said valves close the ports of both pipes 20 and 21. Thus, after the regulating element (the valve 6) has been adjusted so as to reduce the area of the steam passage, the governor sleeve 2 will have the same position as before, so as to preserve and maintain the number of revolutions corresponding to the position of the air-pressure piston 13. The main purpose of the isodromic device (spring 26, cylinder 25, and piston 30) therefore is to maintain a constant engine speed as long as the air-pressure regulator (piston 13) remains stationary, even if the governor 1 should shift the valve 6 to a different position, say on account of a change in the steam pressure or in the vacuum.

Any variation in the power of the driving medium (say live steam) or in the power of the engine actuating the compressor, will cause a shifting of the governor sleeve 2 and therefore an operation of the distributing device located in the cylinder 8, to admit fluid under pressure either above the piston 5 or below said piston 5. The variable or isodromic connection between the speed governor 1 and the throttle valve 6 causes a new condition of equilibrium to be established in the event of any such disturbances in the engine (and not in the compressor), but the number of revolutions is not altered, that is to say, the governor sleeve 2 returns to its original position. The normal rotary speed is affected only in the event of a change of air pressure in the delivery conduit of the compressor, since in this case only the piston 13 will be moved to bring the governor sleeve 2 to a new nor-

mal position, by means of the steps of operations described above.

The valve 6 of Figs. 1, 2, 7 and 8 (and the similar valves 43 and 49 of Fig. 4) are preferably hollow and double-acting, being arranged to throttle both the passage leading directly from the inlet 24' to the outlet 24'', and the indirect passage leading from the inlet 24' through the interior of the valve and over the upper edge of the valve to the outlet 24''. But it will be understood that other types of valves or regulators may be employed.

In Fig. 4 I have shown my improved regulating device (operating as a static pressure regulator, as in Figs. 1 and 2) in conjunction with the governors or regulators of a steam turbine adapted for operation at two different pressures. The regulating device proper is substantially the same as in Fig. 2, the exceptions being as follows: The dash-pot cylinder 25 is secured directly to the piston 5, within the cylinder 22, and instead of the connecting pipe 32 with valve 32', I employ a perforation or channel 32" in the piston 30 to connect the two ends or compartments of the cylinder 25.

The rod 23' projected downwardly from the piston 5 is not connected with the valve 6, as in Figs. 1 and 2, but is pivoted at 34 to a lever 35 fulcrumed at 36. At 37 the lever 35 is pivotally connected with a rod 38, hollowed at its lower end to receive loosely the upper end of a rod 39 which connects the piston 40, movable in the cylinder 41, with the exhaust steam valve 43. The exhaust steam enters at 44' and passes out to the turbine at 44''. A coiled spring 45 tends to close the valve 43. The free end of the lever 35 has a pin or pivot 46 arranged to slide in the guide or loop 47 carried by the upper end of a rod 48 connected with the live steam valve 49. The casing 50 containing this valve is provided with an inlet 50' and with an outlet 50'' through which the live steam passes to the turbine. A spring 51 tends to close the valve 49.

The upper part of the mechanism shown in Fig. 4, being almost identical with that represented in Fig. 2, will operate in the same manner, so that detailed description will not be necessary. Its action on the steam-regulating valves 43 and 49 will be as follows: The valve 43 being hollow, the lower surface of the piston 40 is permanently exposed to the pressure of the exhaust steam in the valve casing 44; the upper surface of said piston is exposed to a constant pressure, as by connecting the upper compartment of the cylinder 41, by means of a pipe 42 or otherwise, with any space or chamber in which a (practically) constant pressure prevails, for instance the

surrounding air. If the pressure of the exhaust steam is sufficient to overcome the force of the spring 45, the exhaust steam valve 43 will be raised until its rod 39 engages the end of the socket on the rod 38. A further upward movement of the valve 43 can therefore take place only when the point 34 of the regulating device moves, or in other words, the further movement 10 of the valve 43 is governed by the regulating device. If the point 34 rises until the pin 46 reaches the upper end of the guide 47 (and no farther), the exhaust steam valve 43 opens more and more, while the live steam valve 49 remains closed. If there should be a relatively considerable reduction of pressure in the delivery conduit with which the pipe 33 is connected, sufficient to raise the piston 5 and the lever 35 until the 15 pin 46 engages the upper end of the guide 47 and lifts the same together with the live steam valve 49, then live steam also will be admitted to the turbine. If then the pressure of the exhaust steam falls below a predetermined limit (depending on the power of the spring 45) the exhaust steam valve 25 43 will close automatically, and the turbine will run exclusively on live steam, the regulating device in this case operating on the live steam valve 49, through the engagement 30 of the pin 46 with the guide 47. Thus the pressure in the delivery conduit of the compressor will be restored to the desired normal value, the number of revolutions not 35 being affected by the operation of the valves 43 and 49 just described.

Fig. 5 shows various positions of the lever 35 and connected parts when operated according to Fig. 4. In position G, the exhaust steam valve 43 and the live steam valve 49 are closed (this is the same position as shown in Fig. 4); in position H, the valve 43 is open, but valve 49 is still closed; in position J, both valves are open.

In Figs. 1, 2, and 4 I employ a regulator affected by the static pressure of the air to keep it as nearly constant as possible; in other words, a static pressure regulator. Instead of this, I may so construct the regulating device as to be affected by the flow of the air and to maintain a practically constant quantity or output of compressed air. The apparatus will be practically the same as described above, except that the connections 50 with the delivery conduit and the means for receiving static pressure or kinetic energy from the fluid therein, will be such that the piston 13, or the rod 14, instead of being operated by a simple static pressure will be actuated by the direct or indirect action of the flow or current of air. This may be obtained by the action of the current flowing through the suction conduit of the compressor, or through the delivery conduit, the 55 movement of the piston 13 being say directly

proportional to the velocity head of said current. In this case, the output or quantity of air delivered by the compressor will be kept constant, and the regulator will be a flow regulator. This kind of regulation may 70 take place, for instance, according to the line D-B of Fig. 3.

When employing the mode of regulation which tends to maintain a constant pressure, the operation will not be disturbed by any 75 changes in the condition of the air entering the compressor such as may result, for instance, from cooling. If for example, the stable condition C (Fig. 3) has been attained, and the air is cooled strongly, the air 80 pressure tends to rise, say to E. Since however the regulating device does not allow the pressure to rise, the apparatus will be adjusted to a condition represented by the point F, which indicates a higher output of air, at 85 the same pressure as that obtaining at the point C, but at a higher rate of speed, being the same rate as would obtain at the point E (points E and F being both on the curve 3). If however the amount of air delivered is 90 not the one corresponding to the point F, but only the smaller amount corresponding to the point C, the regulating device will reduce the number of revolutions to an extent corresponding to the increase in the output 95 of the compressor due to the cooling of the air. Similarly, when employing the mode of regulation which tends to maintain a constant quantity or output of air, any increase in the cooling action will cause the pressure to increase or the number of revolutions 100 to be reduced.

Generally, as constructed hitherto, systems or modes of regulation designed to keep the output constant, were based on the utilization 105 of the kinetic energy in the suction conduit or in the delivery conduit of the compressor. The forms of my invention illustrated by Figs. 1 and 2 however are based on the fact recognized by me that a constant output 110 against varying resistances may also be obtained by employing an air pressure regulator in conjunction with a speed governor, the air pressure operating to adjust the speed governor to the proper number of revolutions. The pressure governor should in this case be so constructed that an increase of air pressure will cause the compressor to rotate at a higher speed, and the regulating device should be so adjusted (say in case of an intended regulation according to the line b-m of Fig. 6) that the engine driving the compressor will make n^4 revolutions per minute when the pressure regulator is in the position corresponding to the pressure at b, 120 but n' revolutions when the pressure regulator is in the position corresponding to the pressure at m.

Such an arrangement is indicated in Fig. 1a, where the connections of the pipes 20, 21, 130

with the respective chambers or compartments of the cylinder 22 are reversed as compared with the arrangement shown in Fig. 1, but in all other respects the constructions 5 are alike, so that the fragmentary showing in Fig. 1^a will be sufficient.

In a similar manner, any particular regulation desired, within the areas found respectively above the line $c-b-e$ and below the line $a-b-d$, said areas being bounded in part by the lines $a-b-c$ and $d-b-e$ (Fig. 6), may be obtained by a proper adjustment of the pressure regulator and of the engine governor according to 10 the air pressure. For instance, such regulation may be effected according to the line $k-l$. The shade lines in Fig. 6 indicate the lower boundary of the area $c-b-e$ and the upper limit of the area $d-b-a$ respectively, and these shade lines have been added merely to better visualize the adjacent boundaries of said areas.

With the hitherto known modes of regulating the output or quantity of air by 25 means of a regulator operated by the kinetic energy of the air, regulation according to the line $k-l$ of Fig. 6 is not obtainable because with these old methods an increase of air pressure will occur only when the 30 amount of air is diminished.

In a like manner, the use of a static pressure regulator was hitherto thought necessary when employing the mode of regulation which tends to keep the air pressure constant. However, just as regulation tending 35 to keep the air output constant may be effected by means depending on the static air pressure, so my invention also enables me to effect regulation tending to keep the air pressure constant, by means of a flow regulator, if this regulator is arranged to adjust the 40 number of revolutions in a manner similar to that described above with reference to Figs. 1, 2, 4 and 5. If, for instance, employing 45 a flow regulator, I desire to effect a regulation maintaining a constant air pressure between the conditions corresponding to the points b and o of Fig. 6, then the governor of the engine driving the compressor 50 should take the position corresponding to the number of revolutions n^4 , when the flow regulator is in the position corresponding to the amount of air at the point b ; while, with the flow regulator in the position corresponding 55 to the point o , the engine governor should take a position corresponding to the number of revolutions n' .

Similarly, any desired regulation indicated on the compressor diagram may be 60 obtained by a proper adjustment of the flow regulator and of the engine governor. However, the modes of regulation lying within the area between the vertical ordinate axis and the line $l-b$, above the curve n^4 , and 65 within the area bounded by the two coördi-

nate axes and the lines $d-b$ and $b-k$ are of special importance in view of the fact that difficulties are experienced when attempting to carry out these modes of regulation by means of a static pressure regulator.

In compressed air plants employing any one of the regulations known hitherto, a decrease in the consumption of air will cause the air pressure to rise. The most advantageous regulation would be the one according to the line $p-q$, in which the air pressure increases slightly with an increasing output, in about the same proportion as the pressure losses in the delivery piping to the place of consumption increase with an 70 increase of the output or consumption. Regulation of the character indicated by the line $p-q$ has not been carried out hitherto, because this was impossible with the means available heretofore. The reason is that 75 whenever the consumption of air decreases (as by throwing out of operation a number of tools operated by compressed air) the air pressure in the distributing pipes of a compressed air plant will rise necessarily. If I 80 attempted to secure a regulation according to the line $p-q$ by means of a static air pressure regulator, for instance according to Figs. 1, 2 and 4, any decrease in the consumption of air would at once set the apparatus (that is, its governor) for a larger output 85 of air, instead of a smaller output; the compressor would thus be adjusted at once to its greatest output or capacity, corresponding to the point r , and not to a reduced 90 capacity, as it should be for a proper operation. My present invention however enables me to apply the above-mentioned advantageous mode of regulation to compressors, 95 since the employment of a flow regulator 100 will adjust the apparatus to a smaller number of revolutions and therefore to a lower air pressure, whenever the consumption of air decreases.

Figs. 7 and 8 illustrate two structures for 110 carrying out this mode of regulation, and Fig. 9 shows a detail of parts which may be substituted for certain portions of either of said two structures. The arrangement shown in Fig. 7 is very similar to that of 115 Fig. 1, differing therefrom practically only by having two pipes 33, 33' connected with the regulator cylinder 7, at opposite ends, instead of the single pipe 33 of Fig. 1. The pipes 33, 33' are connected with the air conduit at points where different pressures prevail, the pipe 33 being connected with the point of higher pressure. This may be done in the same manner as in Fig. 8, where the pipes 33, 33' are connected with the air conduit 33'' at different points of its length, the air flowing in said conduit in the direction indicated by the arrow, so that the pressure will be greater at the pipe 33 than at the pipe 33'. Preferably the conduit 33'' 120

is made with a contraction to increase the difference between the pressures prevailing in the pipes 33 and 33', the former being connected with the conduit at a place where it still has its full width, and the pipe 33' at the narrowest point. The apparatus shown in Fig. 7 will work in substantially the same manner as the one shown in Fig. 1, with this exception that the regulator 7 of Fig. 1, having an air connection 33 only to one side of the piston 13, is a static air pressure regulator, while the regulator 7 of Fig. 7 (and that of Fig. 8 likewise) having connections 33, 33' to lead air of different pressures to opposite sides of the piston 13, is a flow regulator. In one case therefore, the apparatus will respond to variations of air pressure, and in the other to variations in the current of air flowing through the conduit (such as 33").

The regulating device shown in Fig. 8 differs from that shown in Fig. 2 in the same manner as the device of Fig. 7 differs from that of Fig. 1. That is to say, the only material difference between Figs. 2 and 8 is that the former has a static air pressure regulator 7, with a single connection 33, while Fig. 8 shows a flow regulator 7, or a regulator responding to variations in the flow of air, since such regulator has two connections 33, 33' respectively which lead air of different pressures to opposite sides of the piston 13. Further description of the apparatus shown in Fig. 8 and of its operation is therefore deemed unnecessary.

Instead of the regulator parts 7, 13, 16, 33, 33', 33", as shown in Figs. 7 and 8, I may employ the dynamic flow regulator represented in Fig. 9. Here the rod 14 is secured to a disk 13^a which the kinetic energy, assisted by the suction of the air flowing through the channel 33^a of the conduit 33^b, tends to move against the pressure of the spring 16^a, thus operating the lever 9 in the same manner as is done by the piston 13 in Figs. 7 and 8. Instead of the dynamic flow regulator described above with reference to Fig. 9, I may employ any other suitable regulator constructed to respond, in any manner whatever, to the kinetic energy in the air conduit.

In the examples shown in the drawing, the piston 13, or its equivalent, the disk 13^a of Fig. 9, is under the influence of a spring (16 or 16^a) opposing the effect of air pressure. In this case the adjustment or movement of the regulator rod 14 will be proportional to the pressure or flow. Thus, with the structures shown in Figs. 7 and 8, regulation will be effected according to any predetermined almost straight or uniformly curved line. If however instead of the uniformly increasing resistance opposed to the spring 16 or 16^a, I provide means which will oppose an irregularly increasing resistance, I may ob-

tain a regulation following any other (irregular) curve desired. This may be done, for instance, by connecting the compartment below the piston 13, by means of a pipe such as 33', with a chamber in which 70 a constant or a variable pressure prevails, (corresponding, for instance, to the connection of the pipe 33 in Fig. 1), such pressure acting on the piston 13 either alone (in the event of using a variable pressure) or in 75 conjunction with one or more springs. In this manner, I may modify the regulation from the curve $p-b-r$ of Fig. 6 to the curve $p-b-s$, the two curves lying between the same numbers of revolutions or speed curves 80 n' and n'' , but the curve $p-b-s$ showing a materially larger output of air at speeds higher than n' .

It is immaterial to the principle of my invention whether the regulation is carried out 85 partly or entirely by mechanical appliances or by hand, and of course it is also immaterial what kind of engine is governed by the regulator. The particular regulating devices may be employed, as desired, in connection with electric motors, internal combustion engines, steam engines, such as a turbine plant adapted to be operated at two different pressures, etc. In the case of the last-named example, Fig. 4 shows the application 90 of a static regulator to such plant; it will be obvious however, that this apparatus may be converted into a dynamic regulator, responding to variations in the flow of air, by adding connections corresponding to 100 those marked 33', 33" in Fig. 8, or by substituting in connection with the operating rod 14, mechanism such as shown in Fig. 9. In the same manner as in Fig. 4, the supply 105 of steam may be regulated in response to variations in the exhaust steam pressure, by a device operating independently of the air regulation. These and other modifications may be made without departing from the 110 nature of my invention as set forth in the appended claims. It is immaterial of course, whether the apparatus compresses air or any other gaseous fluid.

I claim:

1. In a regulating device for rotary compressors, the combination of a speed governor, a regulator responsive to variations in pressure conditions of the gaseous fluid, an element regulating the operation of the compressor, and operative connections from said 120 element to the speed governor and to the said regulator, said connections including an isodromic member so that the operation of the compressor will vary only in response to variations in the pressure conditions of the 125 gaseous fluid.

2. In a regulating device for rotary compressors driven by steam turbines adapted to be operated at different pressures, the combination of a speed governor, a regulator re- 130

sponsive to variations in the pressure conditions of the gaseous fluid, an element regulating the operation of the compressor by controlling the admission of steam, operative connections from said element to the speed governor and to the said regulator, said connections including an isodromic device, a steam collector, and mechanism governed by pressure in said collector and connected with 5 said regulating element to operate it independently of the action of said regulator and of said speed governor.

3. In a regulating device for rotary compressors, the combination of a speed governor, a regulator responsive to variations in 15 the pressure conditions of the gaseous fluid, an element regulating the operation of the compressor, and operative connections from said element to the speed governor and to 20 the said regulator, said connections including a cylinder connected with one of said parts, a piston connected with the other part, a connection between the chambers of the cylinder on opposite sides of the piston, and 25 a spring tending to restore the normal relative position of piston and cylinder.

4. In a regulating device for rotary compressors, the combination of a speed governor, a regulator responsive to variations in 30 the pressure conditions of the gaseous fluid, an element regulating the operation of the compressor, and operative connections from said element to the speed governor and to 35 said regulator, said connections including a spring and a dash-pot.

5. In a regulating device for rotary compressors, the combination of a speed governor, an element regulating the action of the compressor, a connection between the 40 governor and said element to normally keep the compressor running at a constant speed, a regulator responsive to variations in the pressure conditions of the gaseous fluid, a valve device operated by said regulator, 45 means, controlled by said valve device, for moving said element, and a connection from said valve device to the governor and said element, to restore the valve device to its normal position, the connection of all of said 50 parts being such that the governor will be adjusted for a different normal speed substantially in response to a movement of said regulator.

6. In a regulating device for rotary compressors, the combination of a speed governor, a regulator responsive to variations 55

in the pressure conditions of the gaseous fluid acted upon by the compressor, an element regulating the operation of the compressor, and operative connections from said element to the speed governor and to said regulator, the connection with the regulator being so constructed that an increase in fluid pressure will cause the compressor to rotate at a higher speed. 60

7. In a regulating device for rotary compressors, the combination of a speed governor, a regulator responsive to variations in the pressure conditions of the gaseous fluid acted upon by the compressor, an element regulating the operation of the compressor, and operative connections from said element to the speed governor and to said regulator, the connection with the regulator being so constructed that an increase in the 70 fluid pressure will cause the compressor to rotate at a higher speed, and the regulator being arranged to maintain the flow of fluid 75 per unit of time approximately constant.

8. In a regulating device for rotary compressors, the combination of a speed governor, a regulator for the quantity of gaseous fluid, responsive to variations in the flow of the gaseous fluid through a conduit, an element regulating the operation of the compressor, and operative connections from said element to the speed governor and to said regulator, the connection with the regulator being such as to cause the compressor to rotate at a higher speed when the amount of 90 fluid increases. 80

9. In a regulating device for rotary compressors, the combination of a speed governor, a regulator for the quantity of gaseous fluid, responsive to variations in the flow of 95 the gaseous fluid through a conduit, an element regulating the operation of the compressor, and operative connections from said element to the speed governor and to said regulator, the connection with the regulator 100 being such as to cause the compressor to rotate at a higher speed when the amount of fluid increases, and the regulator being arranged to keep the pressure from falling as the amount of fluid increases. 105

In testimony whereof I have signed this specification in the presence of two subscribing witnesses.
